UNITED STATES PATENT OFFICE.

SILAS E. BAILEY, OF ELMIRA HEIGHTS, NEW YORK, ASSIGNOR TO ELMIRA KNITTING MILLS, OF ELMIRA, NEW YORK, A CORPORATION OF NEW YORK.

GUIDE AND TENSION DEVICE FOR REMOVING SNARLS, KINKS, &c., FROM YARN OR THREAD.

1,254,761.

Specification of Letters Patent. Patented Jan. 29, 1918.

Application filed March 23, 1917. Serial No. 157,010.

To all whom it may concern:

Be it known that I, SILAS E. BAILEY, a citizen of the United States, and resident of Elmira Heights, Chemung county, State 5 of New York, have invented certain new and useful Improvements in Guide and Tension Devices for Removing Snarls, Kinks, &c., from Yarn or Thread, of which the following is a specification.

10 My invention relates to guide and tension devices for yarn and thread.

It is well known that when thread or yarn is pulled or drawn from a cop or cone upon which it has been wound there will be more 15 or less slack in the thread on account of the twist given to the thread when it is wound on the top or cone. When unwinding the slack will cause kinks, loops, snarls and so forth to form in the thread. The yarn or 20 thread, carrying snarls, kinks, etc., must not be delivered in this condition to the knitting or sewing machines in which it is used, else the thread or yarn will be caught in the needle, the goods will be damaged, and 25 other damages and delays will result.

The principal object of my invention therefore is to provide a simple form of a combined guide and tension device which is especially adapted to remove these snarls, 30 kinks, loops, etc., from the yarn or thread before it is delivered to the knitting, sewing or other machines in which it is used.

The above and other objects and the novel 35 features of my invention will be apparent from the following description taken in connection with the drawings which constitute a part of this application and in which:—

40 Figures 1 and 2 are perspective views of guide and tension devices embodying my invention and showing the same mounted on suitable supports; and

45 Figs. 3 and 4 are enlarged side views of parts of the guide and tension devices shown in Figs. 1 and 2 respectively.

50 Referring to the drawing, Fig. 1 illustrates a guide and tension device and its mounting adapted for use with two-thread sewing machines and Fig. 2 shows a similar guide and tension device adapted to be set upon the table of a single thread sewing machine.

55 Referring to Fig. 1 the heavy metal base B has a vertical standard S secured at its center and at its opposite ends it is provided

with suitable supports for the cones or cops 55 10 and 11, respectively, upon which is wound the thread or yarn T to be used in the sewing or other machines. The upper end of the standard S carries a T-shaped coupling 12 which supports the horizontal bar 13 to 60 the ends of which the two guide and tension devices D and D' are connected. These devices are similar to each other in all respects, therefore only one of them will be described in detail.

65 Referring to Figs. 1 and 3 in particular, the tension device D consists of a single length of comparatively stiff, resilient and smooth wire circular in cross section. One end of the straight portion 14 of the wire 70 fits into and is secured in the central opening in the end of the horizontal bar 13. At the outer end of the straight part 14 the wire is bent downwardly and rearwardly as at 15. At the lower end of the part 15 the 75 wire is bent downwardly and forwardly as at 16 to form the lower side of the guide eye or loop G. At the lower end of the part 16 the wire is bent at 17 rearwardly and upwardly parallel to the part 16 to form the 80 upper side 18 of the guide eye G. The sides 16 and 18 of the guide eye G are spaced apart.

85 At the upper end of the side 18 the wire is bent upwardly as at 19 and then downwardly and forwardly as at 20 substantially parallel to the side 18 of the guide eye G. It will be noticed that the bend 19 is spaced from the part 15 to leave a narrow inlet passage 21 at the upper end of the 90 guide eye G through which the thread or yarn may be passed when the eye G is threaded. The lower end of the part 15 prevents the thread T from jumping out of the guide eye G when there is considerable 95 slack in the thread T.

100 The forwardly extending part 20 of the wire constitutes the shank portion of a hook-shape tension member, the free or hook end 22 of which extends upwardly on a curve 105 which is substantially a continuation of the curvature of the shank portion 20. The hook portion 22 prevents the escape of the thread or yarn as it is drawn from the tension member even though the yarn is 110 running loosely.

115 In the form of device shown in Figs. 2 and 4, which is designed for single thread

machines, the heavy metal base B' is provided with a suitable part to receive the cone 23 from which the thread T is drawn. The base B' has a standard S' mounted 5 thereon and an L-shaped coupling member 24 at the upper end of the standard S' carries the combined guide and tension device D². The guide and tension device D² is in most respects similar to the guide and tension devices D, D'. The tension device D² consists of a single length of metal wire circular in cross section and of such a diameter 10 that it will be comparatively stiff. The wire forming the tension device D² has a straight portion 25, the inner end of which fits into and is secured in the opening in the horizontal part of the coupling member 24. At the upper end of the straight part 25 the wire is bent vertically downwardly as at 26 to 15 form the rear side of the guide eye or loop G'. At the lower end of the side 26 the wire is bent forwardly as at 27 and then it is bent upwardly as at 28 parallel to but spaced from the part 26. The bend 27 forms 20 the bottom of the guide eye G' and the upwardly extending part 28 forms the front side of the same. The guide eye or loop G' is open at its upper end at 29 so that it may be readily threaded.

30 At the upper end of the side 28 the wire is bent forwardly as at 30 and then downwardly, and forwardly on a curve as at 31. The part 31 of the wire constitutes the shank portion of the hook-shape tension member 35 of the guide and tension device. The free end of the wire is bent upwardly as at 32 on a curve which substantially forms a continuation of the curve made by the shank portion 31. The hook portion 32, as explained before, is to prevent the escape of 40 the thread or yarn as it runs around and is drawn from the device.

The thread or yarn T may be readily threaded in the guide eyes G or G' of the 45 tension devices and it is then given one or more twists W around the shank of the hook shape tension member, the number of twists depending on the tension desired on the thread when it leaves the guide and tension device. The thread or yarn is delivered 50 downwardly at about an angle of 45° to the sewing or other machine. The pull of the sewing or other machine draws the yarn or thread T from the cone or cop upon 55 which it has been wound and there is usually some slack between the cone or cop and the tension device. On account of the twist given to the yarn or thread when it is wound on the cone or cop, the unwinding 60 operation and slack will permit the formation of snarls, kinks, or loops L therein. As the thread T passes through the guide eye of the device, the loop or snarl L will usually be straightened out since the sides of the eye 65 will catch the loop and hold it until the

thread becomes straight. However, in case the loop or snarl L passes through the eye of the device the tension member will eliminate the loop before it passes the said tension member and thus only straight thread is delivered to the sewing or other machine from the tension member of the device. The thread passes across the space between the bottom of the guide eye and the adjacent part of the shank of the tension member and in its travel across this space all the snarls, kinks and loops which have not previously been removed will disappear. The device is threaded so that the thread passes under one of the parts 18, 20 in Fig. 3 and over the 70 other part and the device in Fig. 4 is threaded so that the thread passes under one of the parts 28 and of the eye G' and over the shank 31 of the hook portion of the device. Due to this arrangement the thread is locked 75 in the device of Figs. 1 and 3 by the inverted loop formed by the sides 18, 20 and the bend 19 and cannot jump out of this loop. In Figs. 2 and 4 the inverted loop formed by the sides 28, 31 and the bend 30 locks the 80 thread in the device. The guide eyes or loops G, G' are deep so as to prevent the escape of the thread or the kinks and loops therefrom and also to prevent the loops becoming caught at the bends 19 or 30 at the 85 upper ends of the guide eyes, since if the loops are caught on any projections the thread or yarn will break and cause damage and delay. The upper end of the hook portion of each of the tension members of the 90 devices is also at a considerable distance above the part of the shank upon which the thread is twisted so that none of the loops or snarls will get caught on the free end of the device, which would also cause 95 breakage of the thread. The free end of the guide and tension device is resilient and will accommodate itself to slight variations in the tension on the thread and will thus 100 also prevent some breaks.

110 It will be seen that the combined guide and tension device is simple in construction and that it may be used with either right or left twisted yarn or thread, since the thread may be twisted on the tension member of 115 the device in either of two ways. The ordinary "pig-tail" guide is adapted for use only with yarn or thread twisted one way and the free end thereof is usually where it will catch kinks in the yarn twisted the other 120 way.

While I have shown and described the construction in detail it is to be understood that various modifications may be made therein without departing from the spirit of the 125 invention.

Having thus described the invention what is claimed and desired to be secured by Letters Patent is:

1. A guide and tension device for remov- 130

- ing snarls, kinks, etc., from yarn or thread, said device comprising a guide eye or loop open at its upper end whereby the yarn or thread may be inserted therein by a movement in a direction transverse of its length, and a tension member connected to said guide loop and extending beyond the closed end thereof, said tension member having an upwardly extending portion to prevent the escape of the thread or yarn as it runs around and is drawn from the tension member.
2. A guide and tension device for removing snarls, kinks, etc., from yarn or thread, said device comprising a wire having a deep guide eye or loop formed therein and open at its upper end whereby said eye may be readily threaded, said wire also having a hook-shape tension member consisting of a downwardly extending shank portion united to the guide eye and an upwardly extending free end to prevent the escape of the thread or yarn as it runs around and is drawn through the device.
3. A combined guide and tension device for removing snarls, kinks, etc., from yarn or thread, said device comprising a single piece of stiff wire circular in cross section having a part doubled upon itself to form a deep guide eye or loop closed at the lower end and open at its upper end whereby said eye may be readily threaded, said wire also having a hook shape tension member formed therein and consisting of a downwardly curved shank portion joined at its upper end to the upper end of one side of said guide eye, the free end of said tension member be-
- ing curved upwardly and forming a continuation of the downwardly curved shank so as to prevent the escape of the thread or yarn from the tension member as it runs around and is pulled through the device.
4. A guide and tension device for removing snarls, kinks, etc., from yarn and thread, said device comprising a base, a standard mounted on said base, and a wire secured at one end to said standard, said wire being provided near its attached end with a guide eye or loop open at the upper end whereby said eye may be readily threaded, the free end of said wire extending upwardly and forming a hook-shape tension member provided with a shank around which the thread or yarn may be twisted to apply tension thereto as it is drawn from the tension member.
5. The combination with a base, of a standard mounted on said base, and a plurality of combined guide and tension devices carried by said standard, each of said devices comprising a guide eye or loop open at its upper end whereby said eye may be readily threaded and a tension member connected to the guide eye or loop and extending beyond the closed end thereof against which the thread or yarn bears in passing through the guide eye or loop, said tension member having an upwardly extending portion to prevent the escape of the thread or yarn as it runs around and is drawn from the tension member.

In testimony whereof I affix my signature.

SILAS E. BAILEY.
